WALTER H. WAKEFIELD, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

WEFT DETECTOR MOUNTED ON INDICATING PLUNGER OF REGULARLY-MOVING TRANSFERRER ARM.

Application filed November 10, 1927. Serial No. 232,422.

This invention relates to improvements in weft detectors of the type mounted on regularly moving transerrer arms and it is the general object of the invention to provide 5 a sliding detector carrier of simplified construction operatively connected at all times to the indicating plunger.

In co-pending application Serial No. 232, 432 filed by Cederlund there is set forth a 10 weft detector mounted on a carrier which is slidably supported on the transerrer arm to move in a direction substantially parallel to the surface being detected. The purpose of making the carrier slidable is to avoid the 15 complication incident to the use of a pivoted carrier due to the fact that the transerrer arm swings in an arc of comparatively small radius. As set forth in said application the carrier is attached to an auxiliary plunger 20 and it is an important object of my present invention to secure the detector carrier directly to the usual indicating plunger.

In the usual construction of transerrer arm carried by detectors the plunger is normally acted upon to move toward indicating 25 position by a compression spring but is constrained from doing so by a pivoted latch which is moved to plunger releasing position at the time of indication of weft exhaustion. 30 It is a further object of my present invention to retain the plunger with its normal tendency to move to indicating position but to eliminate the latch and depend upon the direct action of the detector to prevent the 35 plunger from moving to indicating position when the detector is in contact with sufficient yarn.

With an indicating plunger of the type referred to there is customarily used an indicating lever having a resetting cam effective 40 by the continued upward movement of the transerrer arm to reset the plunger. The device set forth herein depends for its resetting upon an indicating lever of the type specified, the plunger being locked in non-indicating position by a weighted actuator which itself is acted upon by the same spring which tends to move the plunger to indicating position.

With these and other objects in view which will appear as the description proceeds, my invention resides in the combination and

arrangement of parts herein after described and set forth in the claims.

In the accompanying drawings wherein 55 one form of my invention is shown,

Fig. 1 is a vertical section through that part of the transerrer arm which extends over the bobbin to be detected, the parts being in non-indicating position but with the 60 transerrer down,

Fig. 2 is a view similar to Fig. 1 but with the detector moved to an indicating position.

Fig. 3 is a fragmentary top plan view taken in the direction of arrow 3, Fig. 1, and

Fig. 4 is a transverse vertical section on line 4—4 of Fig. 1.

Referring to the drawings the transerrer arm 10 has an extension 11 which projects 70 above and parallel to the bobbin B to be detected and receives a downward movement on each detecting beat of the loom by mechanism not shown but indicated in patent to Ryon No. 1,372,316. An indicating plunger 75 12 is slidably mounted in a portion of the transerrer arm and also extends through a web 13. Spaced walls 14 of the transerrer arm define a vertical slot 15 in which the operating parts of the weft detector are located. A compression spring 16 surrounds 80 a portion of the plunger and the right end thereof exerts its pressure against the pin 17 passing through the plunger, said spring tending normally to move the plunger from 85 the non-indicating position shown in Fig. 1 to the indicating position illustrated in Fig. 2.

An indicating lever 18 pivoted on a fixed 90 part of the weft replenishing mechanism not shown is located above the plunger when the latter is in indicating position with the transerrer arm in its extreme low position. The upper portion of said lever is provided with an inclined cam face 19 which engages the right end of the plunger as the transerrer ascends to move said plunger to the left relatively to the transerrer arm for the purpose of resetting said plunger. This form of lever having the cam face 19 is set forth in patent 95 No. 1,551,219 to Ryon.

In carrying my invention into effect I provide a weft detector carrier 30 which is secured to the left end of the plunger by means of a nut 31 and said carrier extends

upwardly through the slot 15 and is guided by bosses 32 one of which is located on each of the walls 14. By means of the bosses the carrier 30 is held in proper vertical position and is also permitted to slide with the plunger.

The detecting element D is formed with a square shank 33 and has a lower horizontal arm 34 provided with teeth 35 which enter a sufficient supply of weft to prevent sliding movement of the plunger as will be described hereinafter. A compression spring 36 surrounds a portion of the carrier and lies between the upper horizontal arm 37 thereof and shoulder 37' formed on the shank of the detecting element D, said spring 36 normally holding the detector element yieldingly in low position.

The carrier is provided with an intermediate horizontal stop arm 38 to cooperate with the actuator indicated generally at 39. Said actuator is mounted for limited pivotal movement about a pin 40 extending between the walls 14 and has a weighted portion 41 and a stop finger 42 spaced from the weighted portion 41 to define a slot 43 proportioned to receive the stop arm 38 of the carrier. The actuator has depending therefrom a forked arm 44 through which the plunger 45 extends and there is provided a washer 46 held against the forked arm by spring 16. The latter spring is sufficiently strong to lift and hold in raised position the weight 41 so that the latter is normally in the dotted line position shown in Fig. 1 with the stop finger 42 in horizontal alignment with the stop arm 38.

Under normal conditions with the trans- 40 ferrer arm in raised position the detector element will be in its lowest position relatively to the carrier 30 and the actuator 39 will be in the raised or dotted line position shown in Fig. 1. As the trans- 45 ferrer arm descends the horizontal detector portion 34 will engage the surface to be detected and be held against further downward movement as the trans- 50 ferrer arm continues to descend. Shortly thereafter the trans- 55 ferrer arm will come to rest but the weight 41 because of the momentum thereof will continue to move downwardly to the full line position shown in Figs. 1 and 2. This motion of the actuator will take the stop finger 42 out of the path of the top arm 38 so that the latter 60 is opposite the slot 43 and will also place spring 16 under compression because of the forked arm 44. The compressing of spring 16 and the removal of the stop finger 42 does not take place until after the detector has engaged the surface to be detected and when 65 sufficient yarn is present the detector and plunger will be able to resist the pressure of spring 16 bearing against the pin 17 and the plunger will remain in non-indicating position. As soon as the momentum of the

weighted part 41 has been overcome the spring 16 will begin to expand to raise the stop finger 42 in the path of the stop arm 38, this action taking place before the detector becomes completely disengaged from a sufficient supply of weft, so that upon the upward movement of the trans- 70 ferrer arm the parts will be retained in the non-indicating position indicated in Fig. 1.

When insufficient weft is present, however, 75 the friction between the detector and the bobbin is reduced so that the compressed spring 16 will move the detector and carrier together with the indicating plunger to the right as soon as the stop finger 42 moves downwardly out of the path of the stop arm 38. As in the previously described instance the actuator 39 will be acted upon to move upwardly as soon as the momentum of the weighted part is spent, but with the parts in 80 the position shown in Fig. 2 this upward movement will be arrested when the finger 42 engages the underside of the arm 38 as indicated in dotted lines in Fig. 2. As the trans- 85 ferrer arm continues to rise, however, the plunger will engage the cam portion 19 of the indicating lever and will be moved positively to the left, thus carrying the stop arm 38 out of the path of the stop finger 42 to permit the spring 16 to raise the actuator 90 to the normal or dotted line position shown in Fig. 1 relatively to the trans- 95 ferrer.

From the foregoing it will be seen that I have provided a weft detector mounted on a regularly moving trans- 100 ferrer arm wherein the detecting element is mounted directly on the indicating plunger and that the usual form of latch is omitted. It will further be seen that the stops which limit movement of the detector carrier and plunger are dependent for their cooperation upon the weighted actuator and it will further be seen that the detector which prevents the indicating plunger from moving to indicating position when sufficient weft is present also prevents 105 indicating movement of the carrier and holds the plunger while the stop finger 42 is moving out of stopping position. The un- 110 locking and relocking which takes place on each detecting beat of the loom occurs within 115 the time that the detector is in engagement with the yarn. It will also be seen that the inclined portion of the indicating lever serves to move the detector as well as its carrier back to normal position and that the 120 stop finger 42 acts by reason of spring 16 to snap into locking position to retain the parts in normal position.

Having thus described my invention it will be seen that changes and modifications 125 may be made therein by those skilled in the art without departing from the spirit and scope of the invention and I do not wish to be limited to the details herein disclosed, but what I claim is:

1. In a weft detecting mechanism for looms having a regularly moving transerrer arm, an indicating plunger slidably mounted on the transerrer arm, a weft detecting element, a carrier for the element supported by and movable with the indicating plunger, and means tending to move the indicating plunger from non-indicating to indicating position on each detecting beat of the loom, engagement of the detector with a sufficient supply of weft preventing movement of the plunger to indicating position.
2. In weft detecting mechanism for looms having a regularly moving transerrer arm, an indicating plunger slidably mounted on the transerrer arm and normally held in non-indicating position, a weft detecting element supported by and movable with the plunger in a direction substantially parallel to the surface being detected, and means tending to move the indicating plunger and detector element in a direction parallel to the surface being detected on each detecting beat of the loom, engagement of the detector with a sufficient supply of weft preventing movement of the indicating plunger from non-indicating to indicating position.
3. In weft detecting mechanism for looms having a regularly moving transerrer arm, an indicating plunger slidably mounted on the transerrer arm in a direction substantially parallel to the length of the surface being detected, a detector element supported by and movable with the plunger, means normally holding the indicating plunger in non-indicating position, and additional means effective on detecting beats of the loom to tend to move the plunger in a direction parallel to the length of the surface being detected, a sufficient supply of weft engaging the detector to prevent movement of the indicating plunger from non-indicating to indicating position.
4. In weft detecting mechanism for looms having a regularly moving transerrer arm, an indicating plunger slidably mounted on the transerrer arm in a direction substantially parallel to the length of the surface being detected, a detector carrier secured to and movable with the indicating plunger and guided by the transerrer arm, a detecting element slidably mounted on the carrier and yieldingly held in low position relatively to the carrier, means to hold the indicating plunger normally in non-indicating position, and additional means tending on each detecting beat of the loom to move the indicating plunger toward indicating position, a sufficient supply of weft engaging the de-
- tector to prevent movement of the plunger toward indicating position.
5. In weft detecting mechanism for looms having a regularly moving transerrer arm, an indicating plunger slidably mounted on the transerrer arm in a direction substantially parallel to the length of the surface being detected, a detecting element supported by and movable with the plunger in a direction parallel to the length of the surface being detected, a lock normally preventing movement of the detector in a direction parallel to the surface being detected and also preventing movement of the indicating plunger, and means operative on each detecting beat of the loom to unlock the plunger and also exerting a force tending to move the plunger toward indicating position, a sufficient supply of weft engaging the detector to prevent movement of the plunger toward indicating position.
6. In weft detecting mechanism for looms having a regularly moving transerrer arm, an indicating plunger slidably mounted on the transerrer arm in a direction substantially parallel to the length of the surface being detected, a weft detecting element supported by and movable with the detector in a direction parallel to the length of the surface being detected, locking means tending normally to hold the indicating plunger in non-indicating position, and devices operative on each detecting beat of the loom to simultaneously unlock the indicating plunger and exert a force tending to move said plunger toward indicating position, the detecting element when in contact with a sufficient supply of weft preventing movement of the indicating plunger toward indicating position.
7. In weft detecting mechanism for looms having a regularly moving transerrer arm, an indicating plunger slidably mounted on the transerrer arm in a direction substantially parallel to the length of the surface being detected, an indicating lever having a resetting cam face, a detecting element supported by and moving with the indicating plunger, means effective to move the indicating plunger to indicating position when the detector engages an insufficient supply of weft, the plunger engaging the cam face of the indicating lever and moved by the cam face to restore the detector to normal position, and means to hold said detector and plunger in normal position.

In testimony whereof I have hereunto affixed my signature.

WALTER H. WAKEFIELD.
